UNITED STATES PATENT OFFICE.

EMMETT N. HAVERFIELD, OF CADIZ, OHIO.

TIRE-VALVE TOOL.

1,091,839.

Specification of Letters Patent. Patented Mar. 31, 1914.

Application filed February 18, 1913. Serial No. 749,246.

To all whom it may concern:

Be it known that I, EMMETT N. HAVERFIELD, citizen of the United States, residing at Cadiz, in the county of Harrison and State of Ohio, have invented certain new and useful Improvements in Tire-Valve Tools, of which the following is a specification.

This invention has as its object to provide a tool possessing features rendering it highly useful to automobilists and cyclists in working with tire valves.

The primary aim of the invention is to provide a tool which may be quickly and conveniently employed for the purpose of deflating inner tubes, as for example, prior to their removal from the casing. Ordinarily, inner tubes are deflated by pressing in on the valve-stem with a match, nail, or the cap of the valve casing, but this method presents the disadvantage that but one hand can be used in pressing or squeezing the inner tube to completely expel the air. For this reason, the present invention aims to so construct the tool that when applied to the valve casing it will hold the valve in open position without requiring further attention on the part of the user, thereby allowing him to use both hands in expelling the air.

For a full understanding of the invention reference is to be had to the following description and accompanying drawing, in which:—

Figure 1 is a perspective view illustrating the manner in which the tool embodying the present invention is to be employed in deflating an inner tube prior to removing the same from its casing and prior to removal of the casing from the wheel-rim. Fig. 2 is a view partly in side elevation and partly in section of the tool, the same being applied to a tire valve casing. Fig. 3 is a plan view of the tool. Fig. 4 is a fragmentary longitudinal sectional view through the tool.

Corresponding and like parts are referred to in the following description and indicated in all the views of the accompanying drawing by the same reference characters.

In the drawing the tool embodying the present invention is illustrated as consisting essentially of a body 1 which is preferably elliptical in form and flat-sided. At one end the body 1 is formed with a stem 2 and at its opposite end with a stem 3, these stems being in alinement with the major

axis of the said body 1. The stem 2 is formed at its end with a kerf 4 and is thus adapted for use in unscrewing the seat of a tire valve prior to removal of the valve proper. The other stem 3 is provided with threads 5 and flutes 6 which adapt it for use in re-threading the interior of the valve casing. Adjacent that end at which the stem 3 is located, the body 1 is formed with an opening 7, the wall of which is threaded and recessed in the ordinary manner to serve the purpose of a die, and the provision of this opening 7 adapts the tool for use in rethreading the exterior of the valve casing should the threads become distorted or stripped. A rectangular opening 8 is formed in the body 1 near the other end thereof and adapts the device for use as a wrench.

As before stated, the tool is designed for use in deflating inner tire tubes and with this end in view the body 1 is constructed to be fitted to the valve casing and provided with means for holding the valve in open position when the tool is so applied. In arranging the body 1 for application to the valve casing, it is formed in one face at a point substantially midway between its ends with a socket 9, the wall of which is threaded as indicated at 10 and the end or bottom wall of the socket, indicated at 11, is formed centrally with a stud 12 which projects toward the open end of the socket and axially thereof but terminates at its end short of the plane occupied by that face of the body in which the socket is formed. The stud 12 is here shown as cylindrical and its face is flat so as to squarely engage the stem of the valve under conditions which will be presently explained. To permit of the escape of air upon opening of the valve by the engagement of the stud 12 therewith, the body 1 is formed with a vent opening 13 which opens at one end at that side of the body opposite the side in which the socket is formed, and at its other end opens through the end or bottom wall of the said socket, as clearly shown in Figs. 2 and 4 of the drawing.

From the foregoing and from an inspection of Figs. 1 and 2 of the drawing it will be understood that when the tool is to be employed for the purpose of deflating an inner tire tube the tool is disposed with the open end of its socket receiving the end of the valve casing, the cap of the casing

having been previously removed and the tool is then threaded onto the said casing by engaging one's fingers with the stems 2 and 3 and rotating the tool. As the tool is threaded into place, the end of the stud 12 will engage against the upper end of the stem of the valve which, in the drawing is indicated at 14, and will depress the stem to open the valve. The air from the inner tube will then flow through the casing of the valve and escape by way of the vent opening 13. It will be apparent that after having applied the tool to the valve casing, it will require no further attention until the tire has been completely deflated and it is to be removed and consequently both hands may be employed in pressing or squeezing the tire to expel the air therefrom.

It will be observed that inasmuch as the stud 12 terminates short of that face of the body 1 in which the socket 9 is formed, it will not be liable to be bent or have its end battered or spread should the tool be dropped or come in contact with other tools. Furthermore, by so proportioning this stud, the tool may be more readily engaged with and properly centered with relation to the valve casing than would otherwise be the case. It will be observed from an inspection of Fig. 3 of the drawings that the opening 13 at its inner end is of a width equal to the width of the space between the stud 12 and the threaded wall of the socket 9 so that should any dirt enter the socket, the end of a match-stem, or the like, moved over the bottom wall of the socket, will cause dirt lodging upon the said wall to fall through the said opening 13. It is to be noted that the axis of the opening 7, the axis of the stud 12, and the center of the opening 8 are in alinement along the

major axis of the body 1, and consequently when the tool is being applied to a valve casing for the purpose of deflating the inner tube, or when it is being used in rethreading the exterior of the casing or in applying or removing the cap thereof, the stems 2 and 3 serve as handles or finger-pieces, by means of which the tool may be readily rotated.

From the foregoing it will be apparent that when the tool is to be employed for the purpose of deflating inner tubes, the tool is applied to the valve casing in a manner heretofore explained and the air may then be expelled from the tube by pressing upon the tube or squeezing the same.

Having thus described the invention what is claimed as new is:

In a device of the class described, a flat-sided body provided in one face with a threaded socket designed to receive the threaded neck of a tire valve casing, a stud located axially within the socket and projecting from the inner end wall thereof, the stud being spaced from the threaded wall of the socket a distance greater than the thickness of the wall of the neck of the valve casing which the socket is to receive, the body in its other face being formed with a vent which opens through the inner end wall of the socket, the vent at its end which communicates with the socket being of a width substantially equal to the width of the end wall of the socket between its threaded wall and the surface of the stud.

In testimony whereof I affix my signature in presence of two witnesses.

EMMETT N. HAVERFIELD. [L. S.]
